(57) **CLAIM**

The ornamental design for a front fender vent for a vehicle, as shown and described.

DESCRIPTION

FIG. 1 is a front right perspective view of a front fender vent for a vehicle according to the present invention.

FIG. 2 is a front left perspective view of the front fender vent shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is a front view of the front fender vent shown in FIGS. 1-10, but with the front fender vent mounted on a vehicle, and the rest of the vehicle shown in de-emphasized and half-tone portions so as to illustrate environmental structure. These portions form no part of the claimed invention. More specifically, in FIG. 11, the inventive front fender vent is shown within the broken line, and the elements shown outside the broken line form no part of the claimed invention, but are instead included to show environmental aspects thereof.
